CLAIM

The ornamental design for a display screen with graphical user interface, as shown and described.

DESCRIPTION

FIG. 1 is a front view of a display screen with graphical user interface, showing the new design;

FIG. 2 is a front elevation view, shown with an unclaimed environment of an electronic device;

FIG. 3 is a side view thereof;

FIG. 4 is a second side view thereof;

FIG. 5 is a top plan view thereof;

FIG. 6 is a bottom plan view thereof; and,

FIG. 7 is a rear view thereof.

The claim is directed to the individual graphical user interface shown in FIG. 1.

The broken lines of uneven length show the display screen and form no part of the claimed design. The broken lines of

(Continued)

even length illustrate the electronic device and portions of the graphical user interface that form no part of the claimed design.
